UNITED STATES PATENT OFFICE.

WILHELM OHNESORGE, OF DORTMUND, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

TELEPHONE LINE WITH ONE-WAY REPEATER.

Application filed August 23, 1921, Serial No. 494,569, and in Germany December 16, 1915.

(GRANTED UNDER THE PROVISIONS OF THE ACT OF MARCH 3, 1921, 41 STAT. L., 1313.)

For improving the transmission of speech and extending the range of telephonic communications repeaters are generally used which are inserted into the line for amplifying the speaking currents. The methods of inserting the repeaters in the line are commonly based upon the differential or bridge circuit principle, which has however the inconvenience that the effect of the repeater is considerably reduced on account of the subdivision of the output current. For preventing singing the two sections of the line must have approximately the same electrical characteristics. The electrical characteristics vary however continuously in each section of the line so that singing frequently occurs. But before the singing begins the speech may be already distorted or become unintelligible on account of the interference by natural oscillations.

For preventing these troubles two two wire-circuits have already been used with one way repeaters in each circuit so that in each line only the current flowing in one direction is amplified. But this system has the inconvenience that the connection of such a four wire circuit with the ends of a two wire line is not possible. Without this connection the four wire system has however no practical value, as all the telephonic installations actually in use are designed for two wire circuits.

The present invention consists in a method for obviating these difficulties and allowing the connection of such a four wire circuit to the end of a two wire line of usual design. An arrangement according to the invention is shown on the drawing.

The accompanying drawing represents a diagram of a four wire circuit arranged according to my invention. By the four wire circuit which consists of two wire circuits V and W, talking in both directions is possible. Through the two wire circuit V speech currents are transmitted from the left to the right hand in the drawing and through the two wire circuits W in the opposite direction. Two wire circuits a and b are connected to the two long distance wire circuits V and W by means of a Wheatstone bridge and in the long distance circuits

V and W are inserted repeaters R_v and R_w respectively.

To the opposite points g, h; k, i respectively m, n; o, l of two Wheatstone bridges A and B are connected the ends of the long distance two wire lines V, W forming together a four wire line. Two of the branches of each Wheatstone bridge contain each a transformer winding c, d; e, f, the other branches contain each the half of a coil p, q. The winding I of the transformer d is connected to the ends of the two wire line b (distance or subscriber's line), while the winding I of the transformer c is connected with an artificial balancing line x. If the subscriber's line and the artificial line are well balanced the talking current transmitted by the line V to the points i, k of the bridge is subdivided in such a manner that no current passes to the line W connected to the points g, h of the bridge. The current circuit of the bridge is closed without attenuation over the two other branches of the coil q of the bridge. The coil q consists of two halves marked q, q, in the right hand portion of the figure and is bifilarly wound upon its iron core in such manner that when the current flows in parallel through the two halves—i. e. from the point i towards the two outer ends g and h—only ohmic resistance is offered to the current, because in that case the currents flow in opposite direction from the center towards the outer ends and thus their inductive effects neutralize each other. By the transformer d the talking currents are transmitted inductively to the subscriber's line b. If the speech is to be transmitted from the subscriber's line to the four wire circuit the current induced in the winding II by the winding I of the transformer d flows principally through the winding II of the coil e of the balancing line x and the long distance line W, as the coil q of the bridge interposes in this case a high impedance to the passage of the telephonic current.

It is evident that the currents arriving at the points i, k and starting from the top points g, h are considerably weakened on account of the subdivision of the current and the resistances inserted into the circuit.

This has been confirmed by practical experiments. For compensating the losses and furthermore obtaining any desired amplification repeaters may be inserted at the ends 6 of the line V and W, the effect of which may be adapted in a known manner to the two wire line by adjustable resistances. A mutual reaction between the repeaters arranged at the ends and in the middle of the four 10 wire circuit cannot occur as on account of the bridge no or only a very small current is flowing from the line V into the line W. By means of this method in connection with the long distance four wire line provided 15 with one way repeaters at convenient points ranges of communication of any distance (5000 km. and more) are obtainable.

Having now particularly described and ascertained the nature of my said invention 20 and in what manner the same is to be performed, I declare that what I claim is:—

1. A telephone system having in combination a four wire circuit consisting of a separate two wire long distance circuit for 25 each direction, a one way repeater in each of said long distance lines, an artificial balance line, a Wheatstone bridge at the ends of said long distance lines to opposite points of which are connected the ends of the long 30 distance lines, a transformer for each of two

adjacent branches of each bridge, said transformers having one of their windings in circuit with their pertaining branch and having the other windings connected respectively to a two wire line and to said artificial balance line. 35

2. A telephone system having in combination a four wire circuit consisting of separate two wire long distance lines for each talking direction, a one way repeater in each 40 of said long distance lines, an artificial balance line, a Wheatstone bridge at the ends of said long distance lines to opposite points of which are connected the ends of the long distance lines, a transformer for each of two adjacent branches of each bridge, said 45 transformers having one of their windings in circuit with their pertaining branch and having the other windings connected respectively to a two wire line and to said artificial balance line, an inductance interposed in each of the two other adjacent branches of the said Wheatstone bridges and allowing the transfer of the telephonic 50 currents, from the connected two wire circuit, into one of the long distance lines while preventing the transfer to the other long distance line. 55

In testimony whereof I affix my signature.
WILHELM OHNESORGE.
